CLAIM

The ornamental design for a cart handle as shown and described.

DESCRIPTION

FIG. 1 is a top-front-left perspective view of a cart handle according to the claimed design;

FIG. 2 is a front view of the cart handle;

FIG. 3 is a rear view of the cart handle;

FIG. 4 is a right side view of the cart handle;

FIG. 5 is a left side view of the cart handle;

FIG. 6 is a top view of the cart handle; and,

FIG. 7 is a bottom view of the cart handle.

The broken lines in the drawings depict portions of the cart handle that form no part of the claimed design.
